UNITED STATES PATENT OFFICE

2,374,319

FABRIC SPREADER

Joseph Zegarelli, Utica, N. Y.

Application April 25, 1942, Serial No. 440,565

3 Claims. (Cl. 270—31)

My invention relates to a fabric spreader and I declare the following to be a full, clear, concise and exact description thereof, sufficient to enable anyone skilled in the art to which it appertains to make and use the same, reference being had to the accompanying drawing in which like reference characters refer to like parts throughout the specification.

The object of the invention is to provide a device for spreading a bolt of fabric on a long table in such manner that the like surfaces of the fabric will come together when the fabric is spread on the table prior to cutting garments therefrom. More particularly it is desirable to have the nap surface of the fabric laid against the nap surface when the fabric is spread on the table prior to cutting the fabric into garments.

The device will be found particularly useful in spreading a bolt of khaki fabric on a table approximately twenty-five yards long prior to cutting the same into army clothing.

The object will be understood by referring to the drawing in which

Fig. 1 is a perspective view of the device.

Fig. 2 is a detail view showing a rotary bolt carrier and immediate members, parts being shown in sections.

Fig. 3 is a detail enlarged view of a perspective of a V-shaped member employed.

Referring more particularly to the drawing, a carrier frame 1 made preferably of a hollow pipe is supported to move on castors 2, 2 and 3, 3. Castors 2, 2 are not swiveled but straight, whereas castors 3, 3 are swiveled. This combination will allow the frame to be pushed more easily across the room in a straight direction.

Castors 2, 2 and 3, 3 are rigidly attached to the lower ends of standards 4, 4 and 5, 5 which are supported near the lower ends by cross pipe 6, 6. Wooden cross guide bars 10, 10 disposed about half way up standards 4, 4 and 5, 5 and fastened to the said standards by bolts 11, also tend to lend rigidity to standards 4, 4 and 5, 5. Each of the cross bars 10 is beveled at its opposite ends as at 15, whereby to allow the frame an easy approach and to glide along parallel to the upper side boards of the table 16 shown in dotted lines in Fig. 1.

The end standards are held in adjusted relation to each other, whereby to accommodate the frame as a whole to tables of different widths by sleeved cross rods. More particularly the end cross rods are mounted to the upper ends of standards 4, 4 and 5, 5 respectively by fittings 14. Each of the end cross rods comprise a hollow tube

20 and rod 21 which slides into tube 20 a suitable distance and is held by a set bolt 22 near the middle.

The middle cross bar embodies rods 25, 25 that are held in each instance to the upper cross bar 26 of the end frame by a fitting 27. The opposite end of each of the rods 25 projects into the hollow portions of the middle or central bar 30 and have a sliding fit therein. Set bolts 31, 31 are employed to hold rods 25 in predetermined relation to the central bar 30. The hollow open ends of central bar 30 are sufficiently long to permit of considerable adjustment between central bar 30 and rods 25, 25.

The central part of bar 30 is solid, a sleeve 35 is mounted on central bar 30 at the middle thereof. Sleeve 35 has a depending part 36 with a threaded aperture 37. There is also an upstanding part 38 with an aperture that aligns with aperture 37, although not threaded. Furthermore, the upstanding part 38 has an enlarged bearing surface 39.

A complementary part 40 is made on depending portion 41 of sleeve 42. Sleeve 42 is mounted at the middle part of rod 43 which part is solid. A bolt 44 screw threaded at its lower end into the threaded depending part 36 of sleeve 35 projects up through depending part 41 of sleeve 42 and into rod 43 in such manner that sleeve 42 and rod 43 can rotate thereon. Lock nuts 45 hold bolt 44 in place.

Rod 43 is hollow for a portion of its length at both ends for the sliding fit of the adjustable rods 50, 50 which are held in predetermined relation to rod 43 by set bolts 51, 51. Each of the adjustable rods 50, 50 is bent at right angles at 52, 52 to provide uprights having V-shaped open member 53.

Members 53 are adapted to support rod 55 which is projected through the center of the bolt of cloth or fabric 56.

Runways 60 are made in V-shaped members 53 for the insertion of anti-friction balls 57 to aid in lessening the friction between rod 55 and the surface of members 53. Moreover, the open V-shaped members 53 will allow for rods of different diametrical dimensions. End closing members 54 that are bolted or otherwise secured to the ends of V-shaped members to retain balls 57 in runways 60.

U-shaped locking members 61, 61 are pivoted to upright standards 62, 62 for locking rods 50, 50 and contiguous parts from turning on pivot bolt 44. Handle members 63 are formed at right angles to locking members 61, 61. Uprights 62,

62 are anchored in fittings 21, 21. A short stud 64 projects horizontally from each upright 62 to provide a rest for holding member 61 in horizontal locking position. Studs 64 are mounted to uprights 62 just beyond the pivoted mounting of members 61.

In operation, the frame 1 is moved in position to straddle the table 16 and if necessary it can be adjusted as to accommodate the width of the table 16 by resetting bolts 22, 31 and 51, 51.

Rod 55 is inserted through the bolt of fabric 56 and then disposed with its free ends resting in V-shaped members 53, 53. The free end of fabric 56 is partially unrolled manually and brought down under sleeved cross rods 20, 21 and laid on table 16.

Each of the two operators then use one hand at successive intervals to hold the fabric 56 on table 16 and with the other hand simultaneously pushes frame 1 lengthwise of table 16. Bolt 56 will unwind as it moves along table 16 to lay the fabric 56 on the table 16 with nap side uppermost. When the frame reaches the opposite end of table 16, the fabric is cut transversely. The frame is moved then back to original position without unwinding fabric 16. When it reaches the starting position, members 61, 61 are swung upwards, and the bolt of fabric 56 rotated through an angle of 180°, whereby to bring the opposite side of the bolt 56 to face forward and the fabric 56 in position to unwind from the top of the bolt 56 rather than the bottom as in the first place. Members 61, 61 are then lowered to lock rods 43, 43 in position to prevent the bolt 56 from turning, whereupon the frame is again pushed forward, laying the nap of the fabric 56 face down on the upturned nap of the first layer of fabric.

The above movements of frame 1 are repeated and the bolt of fabric 56 is turned each time until the bolt of fabric 56 is completely unwound and laid on the upper surface of table 16.

It will be observed that the frame 1 being independent of the table 16 will prevent any of the parts of said frame 1 from interfering with the upper surface of the table 16 and the laying of the fabric 56.

Having thus described my invention what I claim as new and desire to secure by Letters Patent is as follows:

1. In a fabric spreader a frame having standards supported on rollers, bars attached to said standards for guiding said standards along a table, said frame having rods projecting into a hollow central bar, set bolts for holding said central bar in given relation to said rods, a sleeve mounted on said central bar forming a bearing for another sleeve mounted to turn relative thereto, said last named sleeve supporting a rod having hollow portions, adjustable rods mounted in the hollow portions of said last named rod and having open V-shaped members for supporting a rod carrying a bolt of fabric and U-shaped members mounted on said frame and engaging the rods having open V-shaped members, whereby to hold them in predetermined position.

2. In a fabric spreader a frame mounted on castors, bars attached to said frame to guide the movements thereof, rods carried by said frame 20 and engaging a central hollow bar, a sleeve mounted on said hollow bar forming a bearing, another sleeve mounted thereabove and adapted to turn relative thereto, a rod carried by said last named sleeve having hollow portions, other 25 rods bent at right angles and having open V-shaped members adjustably held to said last named rod, said V-shaped members having anti-friction balls mounted therein, a rod carrying a bolt of fabric mounted in said V-shaped members, upright standards mounted to said frame having U-shaped members pivoted thereto for engaging the rods bent at right angles to hold the same in predetermined position.

3. In a fabric spreader, a frame having standards supported on rollers, bars attached to said standards for guiding said standards along a table, said frame having rods projecting into a hollow central bar, members for holding said central bar in given relation to said rods, a sleeve 40 mounted on said central bar, said sleeve forming a bearing for another sleeve mounted to turn relative thereto, said last named sleeve supporting a rod having hollow portions, adjustable rods mounted in the hollow portions of said last 45 named rod and having open V-shaped members for supporting a rod carrying a bolt of fabric and means mounted on said frame and engaging the rods having open V-shaped members, whereby to hold said rods in predetermined position.

JOSEPH ZEGARELLI.
